(57) **CLAIM**

I claim the ornamental design for an eyeglass case, as shown and described.

DESCRIPTION

FIG. 1 is a front perspective view of an eyeglass case showing my new design;

FIG. 2 is a top plan view thereof shown in a closed position; FIG. 3 is a right side elevational view of FIG. 2, the left side being a mirror image;

FIG. 4 is a rear elevational view of FIG. 1;

FIG. 5 is a front elevational view of FIG. 1;

FIG. 6 is a right side elevational view of FIG. 1, shown in a closed position, with the hanging tab extended;

FIG. 7 is front perspective view of an alternate embodiment of the design shown in FIG. 1;

FIG. 8 is a top plan view of FIG. 7, shown in a closed position;

FIG. 9 is a right side elevational view of FIG. 7, the left side being a mirror image;

FIG. 10 is a rear elevational view of FIG. 7;

FIG. 11 is a front elevational view of FIG. 7; and,

FIG. 12 is a front elevational view of FIG. 7, shown in a closed position, with the hanging tab extended.
